UNITED STATES PATENT OFFICE

132,425

DESIGN FOR A FOOD TRAY OR SIMILAR ARTICLE

Don H. Erickson, Du Bois, Pa.

Application March 20, 1941, Serial No. 99,748

Term of patent 7 years

To all whom it may concern:

Be it known that I, Don H. Erickson, a citizen of the United States, residing at Du Bois, county of Clearfield, in the Commonwealth of Pennsylvania, have invented a new, original, and ornamental Design for a Food Tray or Similar Article, of which the following is a specification, reference being had to the accompanying drawing, forming a part thereof, in which—

Figures 2, 3, and 4 are longitudinal side sectional views in elevation taken along the lines II—II, III—III, and IV—IV, respectively, of Figure 1.

I claim:

The ornamental design for a food tray or similar article, substantially as shown.

DON H. ERICKSON.
